UNITED STATES PATENT OFFICE.

PHIL S. McQUIRK, OF AUDUBON, IOWA.

GOLF BAG.

Application filed June 29, 1925. Serial No. 40,345.

To all whom it may concern:

Be it known that I, PHIL S. McQUIRK, a citizen of the United States, residing at Audubon, in the county of Audubon and 5 State of Iowa, have invented certain new and useful Improvements in Golf Bags; and I do declare the following to be a full, clear, and exact description of the invention, such as will enable others skilled in 10 the art to which it appertains to make and use the same.

My invention relates to improvements in golf bags, and one object thereof is to provide a unique form of closure for the upper 15 end of the bag, including a sleeve to surround the upper portion of said bag, said sleeve being provided with a longitudinal slot which opens through its lower end to receive the usual carrying handle of the bag, 20 provision being made for securing the portions of the sleeve at the lower end of the slot, so that the bag cannot be opened by unauthorized persons.

Another object of the invention is to provide a construction in which the closure 25 above referred to, may be applied to the lower end of the bag when its use is not desired at the upper end thereof.

With the foregoing in view, the invention 30 resides in the novel subject matter hereinafter described and claimed, the description being supplemented by the accompanying drawing.

Figure 1 is a perspective view of a golf bag 35 improved in accordance with my invention.

Figure 2 is a partial side elevation showing the closure applied to the lower end of the bag.

Figure 3 is a side elevation of the closure 40 detached from the bag.

In the drawing above briefly described, the numeral 1 designates a conventional golf bag having the usual carrying handle 2 near its upper end and provided also with 45 a shoulder strap 3 and a ball pocket 4. The numeral 5 designates a closure for the upper end of the bag 1, said closure having a downwardly projecting sleeve 6 to surround the upper portion of said bag. This 50 sleeve is formed with a longitudinal slot 7 to receive the handle 2 and the upper portion of the strap 3, and provision is made for securing the sleeve to the bag, at opposite sides of said slot. In the present 55 showing, links 8 are disposed at the lower corner portions of the sleeve 6, at opposite

edges of the slot 7, and I have shown these links carried by the ends of a strap 9 which is secured to the lower end of said sleeve. The two links 8 are adapted for passage 60 over a staple or the like 10 carried by the bag 1, under the handle 2, and a padlock 11 is provided for engagement with the staple to effectivly lock the closure in place upon the bag, preventing unauthorized persons from opening the latter. 65

Preferably, when the closure is not in use, the sleeve 6 is placed over the lower end of the bag 1 as shown in Fig. 2 and the staple 8 may then be swung over an additional staple 10^a, and held in place by the lock 11. When the device is applied to the bag in this manner, it is not only entirely out of the way, but it forms an effective reinforcement for the bottom of said bag. 70 When either applying or removing the sleeve 6, the slot 7 permits expansion thereof, so that frictional contact with the bag is relieved and the operation may be easily performed. 75

Preferably, the closure is formed of leather with suitable reinforcing stays, such as those indicated at 12 in dotted lines. It is to be understood however that the invention is not restricted to the use of stays, 80 nor to the use of any particular materials. 85

I claim:

1. A golf bag having a carrying handle near its upper end, a staple below the handle, a closure for the upper end of said bag 90 having a downwardly projecting sleeve to surround the upper portion of said bag, said sleeve having a longitudinal slot which opens through its lower end to receive said handle, and a pair of links engaged over the staple for connecting the edges of said slot with each other under said handle.

2. A golf bag having a carrying handle near its upper end, a staple below the handle, a closure for the upper end of said bag having a downwardly projecting sleeve to surround the upper portion of said bag, said sleeve having a longitudinal slot which opens through its lower end to receive said handle, and a pair of links at the lower edges of the slot for engagement over said staple, and a lock associated with the staple to prevent unauthorized separation of the links and staple. 100

In testimony whereof I have hereunto affixed my signature.

PHIL S. McQUIRK.
